TURBINE-BLADE.

1,061,754.

Specification of Letters Patent.

Patented May 13, 1913.

Application filed October 10, 1910. Serial No. 586,288.

To all whom it may concern:

Be it known that I, CHARLES N. F. KNAPE, a citizen of the United States, and a resident of Pittsburgh, in the county of Allegheny and State of Pennsylvania, have made a new and useful Invention in Turbine-Blades, of which the following is a specification.

This invention relates to rotor motors and particularly to means for securing blades to the blade holding element of said motor.

The invention is illustrated as being employed in connection with a turbine of the impulse type in which there is an impulse disk or blade carrying element and blades secured to the periphery thereof by means of calking pieces or keys.

In the drawings: Figure 1 is a sectional view through a blade carrying element showing the blades secured thereto; Fig. 2 is an enlarged fragmentary view of a blade holding element, a blade and a calking piece inserted between the blade and its carrying element; Fig. 3 is a similar view showing the calking piece peened over after insertion; and Fig. 4 is a perspective view of one of the blades.

The blade carrying element may consist of a disk 5 on a shaft 6, said disk being provided with an annular dove-tailed slot 7 having a straight face and an inclined face 9, said slot 7 being provided for the reception of the tail piece 10 of a blade 11. The tail piece and the blade are connected by a web 12 providing a slot 13 for the reception of a flange 14 on the periphery of the disk 5. The tail piece 10 is provided with a straight face 15 to rest against the face 8 of the disk 5 and the end of the tail piece 10 is provided with an inclined face 16 which approximately coincides with the angle of inclination of the face 9, said faces 9 and 16 being spaced apart. Within the space formed by the spaces 9 and 16 an insert or calking piece 17 may be interposed and driven home by any suitable tool, said calking piece 17 being of greater length than the depth of the face 16 so that the projecting end of the calking piece may be bent over against the shoulder 19 of the tail piece

10 to form a lip, said calking piece being effective in securely wedging the blade within the groove 7 of the disk 5. Any tendency of the blade to become loose by centrifugal force during the rotation of the disk 5 will be counteracted by the resistance of the face 8 to the face 15 and any sidewise movement of the blade will be resisted on the one hand by the disk 5 and on the other hand by the calking piece 17 so that after the two are secured together an efficient tight connection will be made.

Having thus described my invention, what I claim is:

1. The combination with an impulse wheel having an undercut groove and a projection and a blade having a slot and projection, the projection on the blade of less width than the width of the slot, the projection on the blade engaging the groove in the impulse wheel and a projection on the impulse wheel engaging the slot in the blade and fitting it, and means between the blade and the inner wall of the undercut portion of the groove for fastening said blade and impulse wheel together.

2. The combination with an impulse wheel and a blade, means for causing the blade and impulse wheel to interengage and a distortable wedge having a bent over end engaging a shoulder on the blade for securing them together.

3. The combination with an impulse wheel having a dove-tailed groove, a blade having a slot engaged by a portion of the impulse wheel which fills said slot, a tail-piece on the blade for engagement with the impulse wheel and a distortable wedge interposed between the tail piece and one edge of the groove and with the undercut portion of the groove, and having one end bent over a shoulder on the blade.

In testimony whereof, I have hereunto subscribed my name this 6th day of October, 1910.

CHARLES N. F. KNAPE.

Correction in Letters Patent

It is hereby certified that in Letters Patent No. 1,061,754, granted May 13, 1913, upon the application of Charles N. F. Knape, of Pittsburgh, Pennsylvania, for a
ment in "Turbine-Blades," an error appears in the printed specification
ing correction as follows: Line 73, for the word "fitting" read *filling*
and that the said Letters Patent should be read with this correction therein that
the same may conform to the record of the case in the Patent Office.

Signed and sealed this 3rd day of June, A. D., 1913.

[SEAL.]

C. C. BILLINGS,

Acting Commissioner of Patents.
